(57) **CLAIM**

The ornamental design for a illuminated level, as shown and described.

DESCRIPTION

FIG. 1 is a front elevational view of the illuminated level of the present invention;

FIG. 2 is a rear elevational view of the illuminated level of FIG. 1;

FIG. 3 is a right side elevational view of the illuminated level of FIG. 1, the left view being a mirror image thereof;

FIG. 4 is a top plan view of the illuminated level of FIG. 1;

FIG. 5 is a bottom plan view of the illuminated level of FIG. 1; and,

FIG. 6 is a top, front, right side perspective in an alternate position (level indicator removed).

The broken lines showing of air bubbles in FIGS. 1,2 and 6 are for illustrative purposes only and form no part of the claimed design.
